[57] CLAIM

The ornamental design for cord retaining reel or similar article, as shown and described.

DESCRIPTION

FIG. 1 is a front elevational view of a cord retaining reel or similar article showing my new design;

FIG. 2 is a right side elevational view thereof, the left side view being a mirror image;

FIG. 3 is a front elevational view of the middle flange taken along the line 3—3 of arrows 3, the rear elevational view thereof being a mirror image thereof;

FIG. 4 is a cross-sectional view taken along the line 4—4 of arrows 4;

FIG. 5 is a front elevational view of a second embodiment thereof, the rear elevational view being a mirror image;

FIG. 6 is a right side elevational view thereof of the reel of FIG. 5, the left side elevational view being a mirror image.

FIG. 1.

FIG. 2.

FIG. 3.

FIG. 4.

FIG. 5.

FIG. 6.
